FASTENER FOR COLD WAVE ROLLERS

Bertha Johnson, Nashville, Tenn.

Application September 15, 1944, Serial No. 554,243

2 Claims. (Cl. 132—42)

The invention relates to a hair wave fastener for a cold wave roll or roller.

The primary object of the invention is the provision of a fastener of this character, wherein hair can be sustained curled about a cold wave roll or roller, the fastener being conveniently actuated in its association with the said roll or roller, either for the holding of the curled or waved hair thereon or the release of the latter without damage to the same.

Another object of the invention is the provision of a fastener of this character, wherein it can be operated with dispatch for the securing of the curl or wave of hair upon the roll or for the removal of the curl or wave from the latter, the fastener being manually controlled at will by the user of the roll for cold waving of the hair in the ordinary well known manner.

A further object of the invention is the provision of a fastener of this character, wherein it is a permanent part of the hair curler or roll, and is handy for prompt service, which is necessary in cold waving the hair, the fastener being novel in construction and unique in the arrangement thereof with the roll.

A still further object of the invention is the provision of a fastener of this character, which is simple in construction, thoroughly reliable and efficient in its purpose, strong, durable, readily and easily operated in its association with the curling roll, and inexpensive to manufacture and install.

With these and other objects in view, the invention consists in the features of construction, combination and arrangement of parts as will be hereinafter more fully described in detail, illustrated in the accompanying drawing, which shows the preferred embodiment of the invention, and pointed out in the claims hereunto appended.

In the accompanying drawing:

Figure 1 is an elevation of the roll with the hair curled thereon and fastened in place by the fastener constructed in accordance with the invention.

Figure 2 is a vertical longitudinal sectional view thereof.

Figure 3 is a view similar to Figure 1 showing the fastener in released position, and the hair curl removed from the roll.

Figure 4 is an end view of the roll and the fastener fragmentarily shown therewith.

Figure 5 is a sectional view taken on the line 5-5 of Figure 3 looking in the direction of the arrows.

Similar reference characters indicate corre-

sponding parts throughout the several views in the drawing.

Referring to the drawing in detail, A designates generally the hair curler or roll having the intermediate concaved area 10 and the outer blunt rounded ends 11 and 12, respectively, which is a common well known construction, and to this curler or roll is attached permanently a fastener denoted at B, constituting the present invention, as will be hereinafter more fully described.

10 as will be hereinafter more fully described.
The fastener B comprises a determined length
of cord 13, which has one end anchored by a
knot 14 in a clearance 15 diagonally disposed to
the longitudinal axis of the curler or roll A in the
15 end 11 with the major portion of such cord free
centrally of such end 11, so that this major por-
tion can be engaged in and drawn through a bi-
furcation 16 provided in the other end 12 of the
roll or curler, to have the intermediate length of
20 the said cord over-ride the hair 17 which is
adapted to be securely rolled on the area 10 for
cold waving purposes by the curler or roll A. The
end of the cord engageable with the bifurcation
16 is formed with a terminal knot 18, so that this
25 end cannot accidentally pull through the cap 19
and become separated therefrom.

Loosely fitted on this cord 13 and removably engageable with the end 12 having the bifurcation 16 therein is a thimble-like holding cap 19 which frictionally slides onto the said end 12 to secure the cord 13 therein and against slippage after adjustment of such cord for the retention of the hair curled on the curler or roll A for cold waving of the hair thereby, yet the said cord 13 can be freed by the removal of the cap 19 from the end 12 to release the curl or wave from the curler or roll A when desired.

The cord 13 is tightened by drawing it through the bifurcation 16 in the end 12 remote from the end 11 of the curler or roll, as is best seen in Figures 1 and 2 of the drawing. The fastener B is manually controlled in the working thereof as before described. The cord so securely holds the hair on the rod, or roller as to prevent its slipping off. The device is well adapted to provide end curls in longer hair.

What is claimed is:

1. A fastener for a curling roll having an intermediate concave curling area and outer blunt ends, comprising a cord secured at one end to one of the blunt ends of the roll and detachably and adjustably engageable in a bifurcation formed in the other blunt end of said roll, and a freely movable cap on the cord and removably engageable on

the said other blunt end of the roll to sustain the cord fast therein.

2. A fastener for a curling roll having an intermediate concave curling area and outer blunt ends, comprising a cord secured at one end to one of the blunt ends of the roll and detachably and adjustably engageable in a bifurcation formed in

the other blunt end of said roll, a freely movable cap on the cord and removably engageable on the said other blunt end of the roll to sustain the cord fast therein and knots on the ends of the cord to retain it secured to the roll and also holding the cap attached to such cord.

BERTHA JOHNSON.
